COMBINED DECORATIVE LIGHT AND ELECTRONIC BUG KILLER

Martin A. Kahn, 1111 Bialock, Apt. 194,
Houston, Tex. 77055

Filed Apr. 25, 1974, Ser. No. 463,906

Term of patent 14 years

Int. Cl. D22—06; D26—03
U.S. Cl. D48—24 R

FIG. 1

FIG. 2

FIG. 3

FIG. 4

FIG. 1 is a front perspective view of a combined decorative light and electronic bug killer incorporating my new design;

FIG. 2 is a side elevational view of the combined decorative light and electronic bug killer;

FIG. 3 is a bottom plan view of the combined decorative light and electronic bug killer; and

FIG. 4 is a top plan view of the combined decorative light and electronic bug killer.

I claim:

The ornamental design for a combined decorative light and electronic bug killer, as shown.
